UNITED STATES PATENT OFFICE.

ARTHUR G. ELLIS, OF EAST LIVERPOOL, OHIO.

EXPLOSIVE-ENGINE.

1,138,648.

Specification of Letters Patent. Patented May 11, 1915.

Application filed January 17, 1913. Serial No. 742,576.

To all whom it may concern:

Be it known that I, ARTHUR G. ELLIS, citizen of the United States, residing at East Liverpool, in the county of Columbiana and State of Ohio, have invented certain new and useful Improvements in Explosive-Engines, of which the following is a specification.

This invention relates to improvements in explosive engines, and the invention is disclosed in connection with a six-cylinder combination having two series of cylinders in parallel and in inclined relation to a single crank shaft between them, all substantially as shown and described and particularly pointed out in the claims.

In the accompanying drawings, Figure 1 is a vertical sectional elevation of a single series of three cylinders and the crank axle and valve chamber therewith, and since the other series is identically the same as this one in all particulars, including the valve chamber and the shaft with which both series are alike connected, the present view is deemed sufficient for both series. Fig. 2, Sheet 2, is an end view of the complete engine reduced in size as compared with Fig. 1 and showing especially the relation of the two series of cylinders to each other. Fig. 3 is a side elevation of Fig 2, both sides being alike. Fig. 4, Sheet 3, is a sectional elevation on a line corresponding to 4-4, Fig. 5. Fig. 5 is a plan view of the engine. Figs. 6, 7 and 8 are cross sections of the valve and valve casing, showing different positions of the valve successively in its operation as hereinafter fully described and taken on lines 6-6, 7-7 and 8-8, respectively, Fig. 9. Fig. 9 is a longitudinal section of the valve alone, and Fig. 10 is a cross sectional view of valve casing and valves corresponding to line 10-10, Fig. 9, and Fig 11 is a cross section on a line corresponding to 11-11, Fig. 9. Fig. 12 is a sectional view showing the cam shaft for the puppet valves.

The foregoing construction and combination of parts affords a six-cylinder engine in which the cylinders *c* and *c'* are arranged in two rows or series of three each disposed at an inward inclination at their bottom relatively to the single crank shaft *s*. The respective cranks 2 of the said shaft are set uniformly at a sixth of a complete circle or revolution apart, and the arrangement of the cylinders in respect to each

other is such that each comes into action and exerts its force in succession to the next preceding one at the predetermined interval so that a practically continuous rotary force is exerted upon the shaft in what is deemed the most advantageous manner possible to apply the power. To these ends the said cylinders work practically in pairs with opposite ones of each series constituting a given pair, and the shaft *s* has its cranks 2 for each pair constructed and arranged to bring the connecting rods of each pair together in crossing relations as seen in Fig. 4. The two rods 3 and cranks 2 for each pair of cylinders are also arranged to come between the bearings 4 for the crank shaft and the rods are offset in respect to one another and have bearing ends *b* for the cranks 2.

The shaft housing *h* has bearings 4 at its ends as well as between pairs of cranks as shown in Fig. 1, and the cylinders are bolted directly to or upon this housing on oppositely inclined seats as seen in Figs. 4 and 5. The said housing is shown as built in two sections longitudinally and bolted together along the flanged edges of said sections as seen in Fig. 3 and is otherwise suitably constructed to fix it in stationary position. In Fig. 1 the cylinders shown are in the series indicated by *c'* for convenience of description.

The valve casing 5 is mounted upon or over the cylinders *c* and *c'*, and said cylinders are provided with water jackets as usual. A single rotary valve *v* is employed for each series of cylinders, and said valve is cylindrical in cross section as shown in this instance and adapted to serve as both a gas supply and exhaust medium for all the cylinders in the same series. To this end a suitable gear mechanism is employed to rotate said valve from the crank shaft *s*, and the said valve is constructed and the said gear is timed to work so as to open the intake and the exhaust passages of the said cylinder according to predetermined times successively. The said valve casing is shown as having two intake or supply openings or ports *m* in its top which, in practice, are connected and open alike to a common source of supply, and there are also a plurality of exhausts *n* here and there through said casing. Distribution of gas is from the said intakes through the center of the valve *v* longitudinally. The *m* reference follows the gas as also does the *n* reference

the exhaust. In its approach to the said cylinders the gas or combustible mixture passes into the interior or bore of the valve for distribution to the cylinders through 5 the two vanned portions 7 of the valve and which serve to intermix and commingle the gas constituents for effective combustion. It will be noticed that the said vanes 7 are set at an inclination or tangent to promote 10 the drawing of the gases into the valve and said vanes are tapered inward for the same purpose. This construction makes the valve a reliable channel of supply through its center to all the cylinders alike and the 15 immediate entrance of the gas from the bore of the valve to each cylinder is by or through the mouth 8, while the exhaust is by a single opening 9 in the valve which communicates with the passage 10 and 20 thence to the further exhaust passage *n* above indicated. In the present showing, Figs. 6, 7 and 8, all the said openings 8 are closed, and a puppet valve 12 in the line of communication and seat at the mouth of 25 passage 10 is adapted to further control both the intake and the exhaust, which have different channels through the valve. The said valve 12 closes automatically under the action of spring 14 on the stem thereof out- 30 side the valve casing, and a bell crank lever 15, or its equivalent, is employed as a medium for positively opening said valve at predetermined times. A single cam shaft 20 in the top of the crank housing is pro- 35 vided for operating said lever 15 through connections 19, there being one cam 21 on said shaft for each pair of cylinders and their puppet valves 12, see Fig 12. The spark plug 16 is positioned in a recess 20 off from the cylinder proper but open thereto opposite the valve 12 where ignition 40 of the gas occurs.

A worm drive gear 30 connects shaft *s* with the valve *v* by means of a shaft 31 45 and bevel gears 22 and 23 or their equivalent, the idea being to time the valve according to the positions of the cylinders for intake and exhaust. By setting the cylinders at an angle of 60 degrees to one another instead of at 120 degrees as has heretofore been the custom, I am enabled to space the cranks at 60 degrees also to obtain a practically continuous crank action. Furthermore, by setting the cylinders in 55 two rows oppositely a six-cylinder machine is made which occupies only half the usual space or length of the cylinders in a single row as usual. This arrangement also materially reduces vibration and affords in- 60 crease of power by concentration. Of course it is known that rotary valves are not broadly new, but this valve being rotary and supported on ball bearings at its ends runs noiselessly and with a minimum of power.

65 The interposition of the puppet valve 12,

between the explosion chamber and the rotary valve 5 serves the important office of preventing the burning gases from coming in contact with the rotary valve during explosion periods and prevents losses by leakage due to such rotary valves when used alone. In other words, the valve 12 sustains both the compression and explosion of the gases and in this way relieves the rotary valve of shock, excessive heating and possible burning out. The puppet valve also serves to promote perfect combustion of the gases, as both the intake and the exhaust are controlled thereby and a perfectly smooth action results regardless of speed of motor and irrespective of springs or other devices for holding the valve open. In this instance each cylinder has a puppet valve as shown, and the said valve has no point of contact between its push rod 24 and the outside of the casing. A spring serves to hold it normally on its seat and it follows that the said seat does not become worn and leaky as is liable to be the case in similar valves generally. It will be noticed especially that as the gas enters the cylinders through the center of the valve 5 and the exhaust is through a jacket or passage about said center there is a preheating of the gas which materially facilitates explosion. The water jacket for said valve is outside the passage *n* for the exhaust, which is about the intake *m*. The exhaust passage through the valve is placed on the outside or surrounding the intake passage so as to be nearest to the water-cooling jacket of the valve casing whereby the most efficient cooling effect is obtained on the valve by both the cool incoming gases and the circulating water in the casing. The exhaust ports are arranged near the respective cylinder-communicating passages 10 and at either side of a pair of intakes 7 to effect quick relief and discharge of the exhaust gases.

Referring now more particularly to the 110 crank shaft *s*, it will be seen that the said shaft has what is termed a single crank for each pair of cylinders with bearings 4 between said cranks, and that each crank has two bearings set one in advance of the other 115 according to the number of engines or cylinders employed. With a six-cylinder engine, as at present, the difference is one-sixth of a revolution and the two connecting rods for each pair of pistons *P* are suitably spaced 120 apart so that each works independently of the other and is offset on the axis of the shaft *s* as seen in Fig. 1, in such manner that the connecting rod 3 of one cylinder inclines constantly as to said axis in one 125 direction and the other inclines in the opposite direction and the division portion 25 between the bearings *b* is especially constructed to accommodate these staggered working relations.

As a résumé of the foregoing it may be observed, first, that the motor is exceptionally compact in length as it occupies only the space necessary for three cylinders instead of six as heretofore by arranging the same in parallel series and in pairs as described. Secondly, that the motor is silent, owing chiefly to the fact that there is but a single puppet valve instead of two for each cylinder and this one working at but half the speed of the ordinary type. Thirdly, the operation is a practically silent one because the valves are mounted on ball or roller bearings and the gears for rotating the same are housed in oil tight casings. Fourthly, the motor has the highest attainable efficiency because of the compactness and solidity of construction as a whole, the quick relief of the exhaust gases, and the thorough admixture of the fuel vapor and air by the fan-like mixing vanes of the valve, and fifthly, the perfect balance in

and between the engines by reason of their arrangement in respect to each other in pairs at sixty degrees instead of one hundred and twenty degrees as between cylinders. 25

What I claim is:

In an internal combustion engine, a series of engine cylinders, a combined intake and exhaust passage for each cylinder and a puppet valve in each passage, in combination with a rotary valve for said several passages in advance of said puppet valves in the passage of gas and a single cam shaft 30 and puppet-valve operating connections with said shaft located between said cylinders and in operating connection therewith.

In testimony whereof I affix my signature in presence of two witnesses.

ARTHUR G. ELLIS.
